UNITED STATES PATENT OFFICE.

WILLIAM P. GRAHAM, OF BROOKLYN, NEW YORK.

DESIGN FOR A PLATE.

45,191.

Specification for Design.

Patented Feb. 3, 1914.

Application filed November 6, 1913. Serial No. 799,620. Term of patent 7 years.

To all whom it may concern:

Be it known that I, WILLIAM P. GRAHAM, a citizen of the United States, residing at Brooklyn, in the county of Kings and State of New York, have invented a new, original, and ornamental Design for a Plate, of which the following is a specification, reference being had to the accompanying drawing, forming a part thereof.

Drawing shows a plan view partially broken away of a plate showing my design.

I claim—

The ornamental design for a plate as shown.

WM. P. GRAHAM.

Witnesses:

J. GLADYS GRAHAM,
MARGARET M. ROY.
